UNITED STATES PATENT OFFICE.

FRANCIS HODGKINSON, OF EDGEWOOD PARK, PENNSYLVANIA, ASSIGNOR TO THE
WESTINGHOUSE MACHINE COMPANY, A CORPORATION OF PENNSYLVANIA.

TURBINE.

1,158,498.

Specification of Letters Patent.

Patented Nov. 2, 1915.

Application filed August 7, 1912, Serial No. 713,792. Renewed April 23, 1914. Serial No. 833,980.

To all whom it may concern:

Be it known that I, FRANCIS HODGKINSON, a subject of the King of Great Britain and Ireland, and a resident of Edgewood Park, in the county of Allegheny and State of Pennsylvania, have made a new and useful Invention in Turbines, of which the following is a specification.

This invention relates to turbines and one of the objects is to provide means for efficiently carrying loads under abnormal conditions as well as under normal conditions.

In practice it is desirable that turbines have overload capacity and, furthermore, in turbines designed to be run condensing it is desirable to have them arranged so that they may carry their normal load running non-condensing. This necessitates passing considerably more steam than would be required for normal load condensing. This has heretofore been accomplished by various means, one of which is to have a valve permitting steam to by-pass entirely around the first stage or in some cases, the impulse wheel. Another method is to have additional or abnormal load nozzles discharging on the same impulse wheel as the normal load nozzles. The first of these is objectionable where the impulse wheel has a large pressure drop because a greater portion of the turbine would sometimes be by-passed than is necessary and the steam would act on fewer turbine elements than would be desirable for the best economy. The latter scheme is sometimes unsatisfactory where the pressure drop is small because then the blade velocity would be too great to effectually utilize the velocity due to expansion in the abnormal load nozzles.

I have provided a device which is here illustrated as comprising a high pressure impulse wheel in which the first expansion of the steam is carried out, the wheel being followed by other turbine elements which may be of any desired construction, but which are here shown as comprising the reaction or Parsons type. It is to be understood that a turbine comprising a high pressure element with two velocity rows and a

stationary row between them and where two or more turbine elements follow, the pressure at the outlet of the first impulse element will vary with the amount of steam passing, so that for normal full load the speed of the buckets on the impulse wheel would be appropriate for the pressure drop selected. If, however, more nozzles are opened and more steam passes into the turbine, the pressure at the outlet of the impulse wheel will rise, resulting in a diminution of velocity through the nozzles so that when the velocity of the impulse blades becomes too great for the efficient utilization of the diminished velocity of steam, the impulse wheel in part becomes a brake. This velocity may drop sufficiently low so that a single row of moving impulse blades would be more efficient than two. With the device herein shown, however, means is provided so that when the velocity has become reduced by passing more steam through the turbine and thus raising the exhaust pressure of the turbine element, the two velocity drops of the impulse wheel are converted into a single drop. The nozzles which furnish steam for the normal loads are arranged to work in the manner just described; that is, passing through the first row, then a segment of stationary blades which will redirect the steam on to the last impulse row. At some suitable point on the turbine, preferably diametrically opposite the normal load nozzles, I may arrange the overload nozzles, that is, nozzles for providing additional steam, and adjacent to the overload nozzles I may provide a segment of a ring which occupies the same relative position as the stationary blades for the normal load nozzles, and this segment serves as a deflector or by-passing element to prevent the steam from impinging upon the second row of blades on the wheel and causing hydraulic friction so that the retardation of the wheel from the different terminal pressures will be lessened if not wholly avoided.

If desired I may employ two groups of nozzles not operated at the same time, using one group for light load when the steam op-

erates on all the blade elements,—or by suitable means shut off steam for this and open to the other group in which the steam will only act on a lesser number of blade elements.

In the drawings: Figure 1 designates a vertical longitudinal sectional view through a turbine constructed in accordance with my invention; and, Fig. 2 is a fragmentary sectional view through that portion of the turbine to which the overload nozzles and baffle ring are attached.

Referring now to the drawings by numerals of reference: 5 designates a turbine casing of the combination type in which is a spindle 6. The spindle carries an impulse wheel 7 provided with two rows of blades designated by the numerals 8 and 9 respectively. Opposite the normal inlet nozzle 10 is a stationary row of blades 11 interposed between the blades 8 and 9 so that the steam at this point has two velocity drops as is common in devices of this character. The steam which may leave the blades 9 may pass from the chamber 12 through the passage 13 and through a second stage 14 of any suitable type, herein shown, however, as the reaction or Parsons type, and as desired, a third stage 15 may be provided. Part of the steam may pass through the stages 14' and 15' and in this manner the spindle 6 will be practically balanced. At some suitable point on the turbine I provide an overload nozzle here designated by the numeral 16 and adapted to admit steam to the first row of blades 8. Instead of the stationary row of blades 11, however, I provide a baffle or segment of a ring 17 which may be secured to the casing 5 by the fastening device 18. This ring 17 effectually by-passes the steam from the blades 8 around the blades 9 so that for overload purposes there is a single velocity drop passing the steam from the blades 8 into the chamber 12 and exhausting through the stages 14 and 15, and thence through the exhaust in the usual way.

In the foregoing it will be apparent that the difficulties above enumerated will be effectually reduced if not wholly eliminated and that a more efficient turbine will be provided than by employing the usual methods heretofore used.

Having thus described my invention, what I claim is:

1. A turbine comprising an impulse wheel having a plurality of rows of velocity blades, a nozzle for admitting steam to the first row to be subsequently directed to at least a second row of blades, a nozzle to admit additional steam to the first row of blades, means for directing the steam from the second nozzle and first row of blades around the second row of blades, an exhaust

port, and an effective row of blades between the velocity blades and the exhaust port.

2. A turbine comprising an impulse wheel having a plurality of rows of velocity blades, a nozzle for admitting steam to the first row to be subsequently directed to at least a second row of blades, a nozzle to admit additional steam to the first row of blades, a baffle for directing the steam from the second nozzle and first row of blades around the second row of blades, an exhaust port, and an effective row of blades between the velocity blades and the exhaust port.

3. A turbine comprising an impulse wheel having a plurality of rows of velocity blades, a nozzle for admitting steam to the first row to be subsequently directed to at least a second row of blades, a nozzle to admit additional steam to the first row of blades, a segmental baffle for directing the steam from the second mentioned nozzle and first row of blades around the second row of blades, an exhaust port, and an effective row of blades between the velocity blades and the exhaust port.

4. A turbine comprising an impulse wheel having a plurality of rows of velocity blades, a nozzle for admitting steam to the first row to be subsequently directed to at least a second row of blades, a nozzle to admit additional steam to the first row of blades, a segmental baffle plate for directing the steam from the second nozzle and first row of blades around the second row of blades, an exhaust port, and an effective row of blades between the velocity blades and the exhaust port.

5. A turbine comprising an impulse wheel having a plurality of rows of velocity blades, a nozzle for admitting steam to the first row to be subsequently directed to at least a second row of blades, a nozzle to admit additional steam to the first row of blades, means for directing the steam from the nozzle and first row of blades around the second row of blades, and a reaction stage coöperating with the impulse wheel.

6. A turbine comprising an impulse wheel having a plurality of rows of velocity blades, a nozzle for admitting steam to the first row to be subsequently directed to at least a second row of blades, an overload nozzle to admit additional steam to the first row of blades, means for directing the steam from the overload nozzle and first row of blades around the second row of blades, and reaction stages on opposite sides of the impulse wheel.

7. A turbine comprising an impulse wheel having a plurality of rows of velocity blades, a nozzle for admitting steam to the first row to be subsequently directed to at least a second row of blades, a nozzle approximately diametrically opposite the first

- mentioned nozzle to admit additional steam to the first row of blades, means for directing the steam from the second nozzle and first row of blades around the second row 5 of blades, and reaction stages on opposite sides of the impulse wheel.
8. In combination in a turbine, a plurality of rows of impulse blades, a nozzle for delivering motive fluid to the first row of 10 blades, additional blades for receiving motive fluid delivered from said impulse blades, and means for directing motive fluid issuing from one row of impulse blades around the next adjacent row, and to the additional 15 rows of blades.
9. In combination in a turbine, a plurality of rows of impulse blades, a nozzle for delivering motive fluid to the first row of blades, additional blades for receiving motive 20 fluid after it has traversed at least one row of impulse blades and a deflector for directing motive fluid delivered from one row of impulse blades around the next adjacent row and to said additional blades.
10. A turbine comprising a series of rows 25 of blades, a fluid inlet for delivering motive fluid to the first row of blades of the series, a second series of rows of blades for receiving motive fluid which has traversed at least one row of blades of said first series, and a deflector located within the turbine casing and between adjacent rows of blades of the first series for deflecting motive fluid issuing from one row around the adjacent row 30 of the blades of the first series and to the blades of the second series.
11. In combination in a turbine, a series 35 of rows of impulse blades, a nozzle for delivering motive fluid to the first row of blades of the series, an additional series of rows of blades located between said first mentioned series and the exhaust of the turbine for receiving motive fluid from the first mentioned series, a deflector mounted on the turbine casing and located between adjacent rows of blades of the first series, and having a passage formed therebetween and the casing for delivering motive fluid deflected thereby to the additional series of 45 blades.
12. In combination in a turbine, a plurality of rows of impulse blades, a nozzle for delivering motive fluid to the first row of blades of the series, an additional row of 50 blades between the impulse blades and the turbine exhaust for receiving motive fluid delivered from the impulse blades, a deflector located between the adjacent rows of impulse blades and having a passage formed therebetween and the turbine casing.
13. In combination in a turbine, a row of 55 blades, a nozzle for delivering motive fluid to the blades, a delivery passage extending into the turbine casing and communicating 60 with the nozzle and having a fluid delivery opening formed therebetween and the turbine casing.
14. In combination in a turbine, a plurality of rows of impulse blades, a nozzle for delivering motive fluid to the first row 65 of said blades, additional rows of blades for receiving the motive fluid from the impulse blades and located between the impulse blades and the turbine exhaust, a deflector located between adjacent rows of impulse blades for 70 directing the fluid issuing from one row of blades around the next adjacent row of blades, and a fluid delivery passage extending into the casing and communicating with the nozzle and having a fluid delivery space 75 formed between it and the turbine casing.
15. In combination in a turbine, a plurality of rows of impulse blades, additional blades for receiving fluid from said impulse blades, a fluid delivery nozzle for delivering 80 motive fluid to the impulse blades, a second nozzle for delivering fluid to the first row of impulse blades, and a deflector mounted on the turbine and extending between two adjacent rows of the impulse blades for 85 deflecting fluid discharge from the second nozzle around at least one row of the impulse blades to the additional blades after it has traversed at least one row of the impulse blades.
16. In combination in a turbine, a fluid delivery nozzle, a plurality of rows of impulse blades receiving fluid from said nozzle, a divided flow stage for receiving motive fluid from the impulse blades, a second nozzle for 90 delivering fluid to the impulse blades, and a deflector mounted on the turbine casing and extending between adjacent rows of the impulse blades and having a fluid delivery passage formed between it and the 95 turbine casing, said deflector deflecting fluid delivered from the second nozzle around at least one row of impulse blades to the divided flow stage after the fluid has traversed at least one row of the impulse blades.
17. A turbine comprising a casing, a rotor within the casing, two series of blades mounted on the rotor, the second series of which is divided into two sets located on opposite sides of the first series and both 100 adapted to receive motive fluid therefrom, a fluid delivery nozzle for delivering motive fluid to the first series of blades and a fluid delivery passage extending into the turbine stator, and communicating with the 105 nozzle and having a fluid passage formed between it and the casing.
18. A turbine comprising a casing, a rotor within the casing, two series of blades mounted on the rotor, the second series of 110 which is divided into two sets located on opposite sides of the first series and both adapted to receive motive fluid therefrom, a

fluid delivery nozzle for delivering motive fluid to the first series of blades, a fluid delivery passage extending into the turbine stator, and communicating with the nozzle and having a fluid passage formed between it and the casing, and a deflector located between adjacent rows of the first series of blades and having a fluid delivery passage formed therebetween and the turbine casing.

In testimony whereof, I have hereunto ¹⁶ subscribed my name this first day of August, 1912:

FRANCIS HODGKINSON.
